JACOB ORESTER AND WILLIAM JOHN GEE, OF SYRACUSE, NEW YORK

DESIGN FOR A LICENSE PLATE HOLDER

Application filed February 13, 1931. Serial No. 38,651. Term of patent 7 years.

To all whom it may concern:

Be it known that we, JACOB ORESTER and WILLIAM J. GEE, citizens of the United States, residing at Syracuse, in the county of Onondaga and State of New York, have invented a new, original, and ornamental Design for License Plate Holder, of which the following is a specification, reference being had to the accompanying drawings, forming part thereof.

Fig. 2 is a top plan view of a license plate holder; and

Fig. 3 is an end view of a license plate holder.

We claim:

The ornamental design for a license plate holder, as shown.

JACOB ORESTER.
WILLIAM JOHN GEE.
